DESIGN FOR A LADY'S HAT OR SIMILAR ARTICLE

Lillian P. Burnside, New York, N. Y.

Application April 29, 1943, Serial No. 110,077

Term of patent 3½ years

To all whom it may concern:

Be it known that I, Lillian P. Burnside, a citizen of the United States of America and resident of the city, county, and State of New York, have invented a new, original, and ornamental Design for a Lady's Hat or Similar Article, of which the following is a specification, reference being had to the accompanying drawing, forming a part thereof.

In the drawing,

Fig. 1 is a top view of a lady's hat embodying my design, and

Fig. 2 is a front perspective view thereof.

I claim:

The ornamental design for a lady's hat or similar article, as shown.

LILLIAN P. BURNSIDE.
